UNITED STATES PATENT OFFICE.

WALTER L. LILLIE, OF COLUMBUS, OHIO, ASSIGNOR TO THE WALTER L. LILLIE COMPANY, OF COLUMBUS, OHIO, A CORPORATION OF OHIO.

DESIGN FOR A CABINET.

Application filed September 12, 1921. Serial No. 500,221. Term of patent 3½ years.

To all whom it may concern:

Be it known that I, WALTER L. LILLIE, a citizen of the United States, residing at Columbus, in the county of Franklin and State of Ohio, have invented a new, original, and ornamental Design for Cabinets, of which the following is a specification, reference being had to the accompanying drawing, forming part thereof.

The figure is a perspective view of a cabinet, showing my new design.

I claim:

The ornamental design for a cabinet, as shown.

WALTER L. LILLIE.
